UNITED STATES PATENT OFFICE.

ERNEST LUNSFORD, OF ATLANTA, GEORGIA.

INNER SEAL FOR CASKETS.

Application filed August 8, 1925. Serial No. 49,116.

This invention relates to an improvement in inner seals for caskets, and aims to provide a simple, effective and reliable means for firmly and securely mounting the glass or transparent panel on the metal frame member of the inner seal in such a manner that the proper packing and tight securing action is had without danger of cracking the glass.

10 A further object resides in the provision of a device of this character which is of simple and durable construction, reliable and efficient in operation and easy and comparatively inexpensive manufacture.

15 Other objects and advantages reside in certain novel features of the construction, arrangement and combination of parts which will be hereinafter more fully described and particularly pointed out in the 20 appended claims, reference being had to the accompanying drawings forming a part of this specification, and in which:—

Figure 1 is a fragmentary view partly in section and partly in elevation showing one 25 embodiment of the invention, and

Figure 2 is a similar view illustrating another embodiment of the invention.

Referring to the drawings it will be seen that in all embodiments of the invention an 30 inner seal, designated generally at 10, is provided and is adapted to be mounted on a casket (not shown) in the usual way. In accordance with the usual practice the inner seal includes an open rectangular frame 12 35 and a glass or transparent panel 13.

The present invention aims to provide a novel mounting for the glass 13 on the frame 12 and to this end the frame 12 is formed around its upper marginal edge with an annular inwardly directed flange 14 having a 40 downwardly extending lip 15 around its inner edge.

In the form of the invention shown in Figure 1 externally threaded depending 45 studs 16 are provided at regular spaced intervals around the underside of the flange 14, the upper ends of the studs 16 being spot-welded to the underside of the flange 14. A strip 17 is placed up against the inner face 50 of the flange 14 and is confined and concealed by the lip 15 although the packing strip is of such a size as to extend down at least as far as the lower edge of the lip 15 when subjected to maximum compression.

55 The packing strip may be of any elastic packing or it may be of soft lead. The up-

per marginal edges of the glass 13 are engaged by a similar strip 18. The strips 17 and 18 are narrow and are located between the studs 16 and the lip 15. Fastening 60 means is provided for holding the glass in proper position and for urging the packing strips 17 and 18 into engagement with the glass and the packing strip 17 into engagement with the flange without subjecting the 65 glass to cracking strains while placing the necessary compression on these parts. For this purpose this fastening means comprises an angular element 19 which may take the form of a lug for each stud 16 or which may 70 take the form of a plate or frame having openings receiving the several studs. The fastening element 19 has a portion 20 engaging the flange 14, as at 21, and a portion 22 engaging the packing strip 18 and formed 75 with an opening 23 for each stud. Nuts 24 are threaded on the studs and engage the portions 22 of the clamping elements 19. With this arrangement when the nuts 24 are tightened up the glass is secured in position and the packing is placed under the desired compressions, the action of the nuts being transmitted through the resilient clamping element the resiliency of the 80 clamping element being interposed between the nuts and the packing precludes the possibility of destructive strains being set up in the glass.

In the form of the invention shown in Fig. 2 the studs 16 are omitted and relatively wide packing strips 25 and 26 replace the narrow packing strips 17 and 18. The resilient clamping elements 19 are employed and are urged into co-operative engagement with the packing strip 26 by means of set 85 screws 27 having threaded engagement with internally threaded openings of arms 28 of brackets 29, the brackets 29 having portions 30 spot-welded to the frame 12. The action of this embodiment is essentially the 90 same as that hereinabove described.

The packing strips may be of any elastic packing or of soft lead as hereinabove set out, but preferably these packing strips are composed of a composition of asbestos and 95 ground lead.

I claim:—

1. An inner seal for caskets including a frame having a flange and a glass, comprising packing strips engaged with the glass, 110 one of the packing strips being engaged with the flange, a resilient clamping element

engaging the lower packing strip and the flange, brackets carried by the frame, and set screws threaded on the brackets and engaging the resilient clamping elements.

- 5. 2. An inner seal for caskets including a frame member having an inturned flange and a glass and comprising packing strips engaged with the upper and lower marginal edges of the glass, the upper packing strips engaging the underside of the flange, means for holding the packing strips and glass in position and for compressing the packing strips and consisting of fastening means,

resilient means interposed between the fastening means and packing strips and comprising angular clamping elements constructed of resilient metal, each angular clamping element having a substantially vertical portion having its upper end engaging and fulcrumed on the juncture of the flange and frame, each angular clamping element also having a substantially horizontal portion engaged on one side by the fastening means and on the other side by the lower packing strip.

ERNEST LUNSFORD.
